PIVOTED BREECH BLOCK LOCKING
MECHANISM

Börje Sahlin, Stockholm, and Edvin Emanuel Jansson, deceased, late of Bofors, Sweden, by Halvar Nyqvist, executor, Bofors, Sweden, assignors to Aktiebolaget Bofors, Bofors, Sweden, a joint stock company of Sweden

Application May 6, 1948, Serial No. 25,485
In Sweden March 29, 1945

2 Claims. (Cl. 89—190)

1

It is previously known in automatic firearms to effect the return of the breech and the ejection of the cartridge cases by the direct action of the powder gases on the base in the shell bearing against the breech, and it is known, likewise, to gain the same effect by mechanical actuation of members brought into movement by a recoiling effect.

Both of these arrangements operate satisfactorily in fine-bored firearms, but with larger bores the first-mentioned type of arrangements operates too slowly, while the latter type involves constructions, too cumbersome, which do not operate satisfactorily.

According to the present invention, the problem has been solved by a combination of said two arrangements known per se, inasmuch as the return of the breech and thus the ejection of the cartridge case and the storing of energy for the other working operations of the firearm is effected by the powder gases acting directly on the bottom in the case, after an unlatching fork actuated by the recoil has unlatched the breech-lock, loosened the case and imparted the breech and the case with a certain rearward initial speed.

The invention is illustrated in the accompanying drawing, wherein Fig. 1 represents a diagrammatic vertical longitudinal section through a portion of a firearm according to the invention, this figure showing the position of the parts at the moment of firing. Fig. 2 is a detail section on line II—II in Fig. 1. Fig. 3 is a longitudinal detail section showing the position of the parts immediately after the firing moment. Fig. 4 is a detail section on line IV—IV in Fig. 3. Fig. 5 is a longitudinal detail section showing the position of the parts immediately before the termination of the recoiling movement. Fig. 6 is a longitudinal detail section showing the position of the parts during the forward movement of the breech.

In the drawing, 1 designates the barrel of a firearm, said barrel being displaceably mounted in a guide sleeve—not shown—and in a recoiling jacket 4 coupled to the guide sleeve, an advancing spring 5 being arranged between said recoiling jacket and the barrel. Screwed fast to the barrel 1 is a breech guide 6, which is provided with two depending lugs 7, in which an unlatching fork 8 with two fork shanks 8' is pivoted on a shaft 9, which is retained in its position by the sides 4' of the recoiling jacket 4. Fork shanks 8' move between two abutments (not shown). The unlatching fork may of course be mounted in some other part of the recoiling system.

2

The bearing pin of the unlatching fork 8 is so arranged relatively to an abutment 53 arranged on the recoiling jacket 4 that a driving arm 52 on the unlatching fork when recoiling will strike against the abutment 53 so as to be stopped by said abutment, the unlatching fork being thus caused to swing about its shaft 9. The rear end of a non-rotatable breech 12, which is displaceable in the longitudinal direction in the casing 6 against the action of a spring device, not shown, strikes during its rearward movement against a cushioning-device (not shown) to be stopped by the latter.

A striker 16 provided with a priming pin 35 is displaceably arranged in the breech 12 in the longitudinal direction thereof, said striker being actuated by a striker spring and having a transverse recess 36 adapted to receive a striker bridge 37, which is somewhat displaceable relatively to the breech 12 in the longitudinal direction thereof. The striker bridge 37 is displaceable by means of the shanks 8' of the unlatching fork.

The striker bridge is provided with oblique cam surfaces 48 cooperating with oblique cam surfaces 47 on breech latches 46, which are swingably or displaceably arranged in the breech 12, to bring said latches 46 out of engagement with stop abutments 51 arranged in the casing 6.

The mode of operation of the arrangement is as follows, starting from the position of the parts at the moment of firing, as shown in Fig. 1. The breech is locked to the tube, while bearing on the rear end of the cartridge introduced into the cartridge chamber, by means of the breech latches 46 and the abutments 51 over the breech guide 6 screwed fast to the barrel 1. The striker 16, the priming pin 35 and the striker bridge 37 are in their foremost position, the priming pin having struck the percussion cap of the cartridge. On account of the jarring bottom pressure produced at firing, the recoiling system, that is to say the tube with the breech guide and the breech, move rearwardly. At the commencement of the recoiling movement, the driving arm 52 of the unlatching fork 8 hits the abutment 53 of the recoiling jacket 4, so that the unlatching fork 8 is swung about its shaft 9 and the fork shanks 8' thereof move the striker bridge 37 rearwardly, which in turn, at straining of the striker spring 39, moves the striker 16 and the priming pin 35 rearwardly, while releasing with its oblique cam surfaces 48 the engagement between the breech latches 46 and the abutments 51, so that the breech is made free and will have a rearward initial movement imparted thereto so as to strain operating springs, not shown. During the con-

tinued rearward movement of the breech, the pressure of the powder gases act on the shell bottom, which in turn presses against the breech and imparts the continued rearward movement to the same. The recoiling system continues its rearward movement at compression of the advancing spring 5. During the rearward movement of the breech, the feeding of the cartridges takes place in a manner which need not be discussed in this connection.

The invention is not confined to the example shown, inasmuch as many alterations may be undertaken within the scope of the invention. For example, the unlatching member may be adapted to actuate the breech directly after the unlatching operation. Also, the unlatching member need not necessarily be bifurcated.

Having now described our invention, what we claim as new and desire to secure by Letters Patent is:

1. In an automatic firearm having a short barrel recoil in the longitudinal direction, said firearm having a recoiling system which includes a recoil jacket, a positively closed breech block, and at least two breech latches each provided with an oblique cam surface and arranged between said breech and said recoiling system for locking or unlocking said breech to said recoiling system, said breech latches being positioned in an oblique position in relation to said longitudinal direction when said breech is locked to said recoiling system, breech unlatching mechanism, which includes, in combination, an abutment positioned on said recoil jacket, a pivot shaft fixed to said recoiling system; a pivoted unlatching member pivoted on said pivot shaft, whereby said pivoted unlatching member, when said firearm is fired, strikes against said abutment stop and is thereby caused to pivot about said shaft; and an element operatively disposed so as to be moved by said pivoted unlatching member as it pivots about said shaft; said element being provided with at least two obliquely disposed cam surfaces at its rearward end, whereby said cam surfaces, when they strike against the cam sur-

faces of the said breech latches upon rearward movement of said element, act so as to unlatch said breech latches and thereafter act so as to impart a rearward initial movement to said breech, after said breech latches have been unlatched.

2. An automatic firearm according to claim 1, wherein said firearm also includes a striker, and engagement abutments wherewith said breech latches are pivotally arranged in the breech, wherein the pivoted unlatching member of said breech unlatching mechanism consists of a fork member, the shanks of said fork being so disposed as to move said element, and wherein said last-named element comprises a striker bridge extending transversely through said striker, said striker bridge being displaceable relative to said breech in the longitudinal direction of said breech, and said striker bridge further being provided with said oblique cam surfaces cooperating with said oblique cam surfaces on said breech latches whereby, when said cam surfaces are brought into operative engagement by movement of said pivoted unlatching member, said breech latches are swung out of contact with said engagement abutments of said firearm.

BÖRJE SAHLIN.

HALVAR NYQVIST,
*Executor of the Estate of Edvin Emanuel Jansson,
Deceased.*
